UNITED STATES PATENT OFFICE.

EVERETT E. SHELDON, OF PHILADELPHIA, PENNSYLVANIA.

PHOTOGRAPHIC-PRINTING MACHINE.

1,377,099.

Specification of Letters Patent.

Patented May 3, 1921.

Application filed May 21, 1920. Serial No. 383,039.

To all whom it may concern:

Be it known that I, EVERETT E. SHELDON, a citizen of the United States, residing at Philadelphia, in the county of Philadelphia and State of Pennsylvania, have invented 5 new and useful Improvements in Photographic-Printing Machines, of which the following is a specification.

The invention relates to photography and 10 more particularly to machines for printing or making positive reproductions from photographic negatives and to this end it has for an object the provision of a machine which will quickly and expeditiously accomplish this result.

The invention comprehends among other features the provision of a machine which primarily provides a light-tight box preferably divided into a plurality of compartments 20 in one of which is carried a suitable light whereas the other compartment receives on a transparent face or in an opening thereof, the film and printing paper so that upon the subsequent opening of a door 25 or closure connecting the two compartments, the light in the one compartment will illuminate the other compartment and bring about the printing action between the film or plate and the printing paper to accomplish the desired result. With this in mind 30 the use of a presser member for holding the printing paper against the film or plate is provided in such manner that when the presser member is brought into operating position, the closure between the two compartments will be automatically opened for 35 the passage of the rays of light. I preferably have the closure made of a red glass or film so that when the closure is in normal or closed position the forward compartment will be illuminated by a red light from the lamp in the rear compartment, thus facilitating the disposition of the film or plate and enabling the operator to readily 40 discern the particular character of strength of the representation on the film or plate, the mentioned closure furthermore being so mounted that if desired it can be independently operated to be held in an open position 45 at all times or normally arranged to open only when the presser member is brought into operating position and closed upon the subsequent removal of the presser member from contact with the printing paper.

In the further disclosure of the invention 55 reference is to be had to the accompanying drawings constituting a part of this specification, in which similar characters of reference denote corresponding parts in all the views, and in which,—

Figure 1— is a side elevation of the machine, the presser member being shown in operating position.

Fig. 2— is a plan view of the structure shown in Fig. 1.

Fig. 3— is an enlarged fragmentary plan view of the closure operating device mechanism, the presser member and its mountings having been removed.

Fig. 4— is a vertical longitudinal sectional view taken through the printing machine with the presser member shown in inoperative or raised position.

Fig. 5— is a fragmentary vertical sectional view taken on the line 5—5 in Fig. 75 4, and

Fig. 6— is a fragmentary vertical sectional view slightly enlarged, taken through the mat or film holding member.

Referring more particularly to the views, 80 the numeral 10 indicates a box which at its forward end is provided with a suitable inclined support 11, the front 12 being also suitably inclined as shown on its inner face carrying a mirror 13. The box is divided 85 into two compartments 14, 15, the former being termed the rear or light compartment and the latter the front or printing compartment. The rear compartment carries a suitable light 16 in front of a reflector 17 and a stack 18 is provided as an outlet from the compartment 14 to take off the heat which may be produced by the light 16. The rear compartment has a door 19 and on which the reflector 17 and light are preferably mounted 90 so that ready access can be had to the same when the door is opened. The compartments 14, 15, are formed by the structure of the box and an interposed partition or wall 20 having an opening 21 normally closed by 95 a closure 22, the latter preferably consisting of a piece of red glass suitably mounted in a frame 23 which is mounted to swing on suitable hinges 24. The front compartment 15 has a horizontal opening 25 in which may be disposed a framing member 26 upon which is adapted to be placed the usual film or plate and it will be clear that when a film 100

or plate has been arranged in position over the opening 25 the subsequent opening of the closure 22 will cause the rays of light from the lamp 16 to be projected on to the 5 mirror 13 and thence deflected on to the film or plate, bringing about the printing of the representation of the film or plate on to the printing paper. When the closure 22 is in the normal position shown in Fig. 4, the 10 rays of light from the lamp passing through the red glass 22 will bring about but a weak transmission of light to the front compartment and which light will be of a red color so as not to affect the printing paper al- 15 though it will be apparent that this red light will be of sufficient intensity and strength to permit of the operator disposing the film or plate in position and observing the intensity of the impression or picture on 20 the negative so that he can judge the length of time of exposure of the printing paper in order to obtain the desired result. Thus it is of great advantage to employ the red glass closure rather than an opaque member.

25 The closure 22 carries an upright 27, to which is pivoted an angularly extending link 28, in turn pivoted to a swinging arm 29 suitably swiveled at 30 and extending exteriorly of the compartment 15 with an extension 31 on the exterior end of the arm and a suitable roller 32 carried on the extension. When pressure is brought to bear against the rollers 32 to actuate the extension and swing the arm 29, it will be clearly seen 35 that the link connection with the upright and closure will bring about a swinging of the closure from its normal closed position shown in Fig. 4, to an open position, un- 40 covering the opening 21 to permit of the passage of the rays of light from the lamp directly into the compartment 15. Fig. 5 shows a spring 33 connected by a cord 34 to the arm 29, so that the closure 22, when pressure on the rollers 32 is released, will 45 be returned to closed position as to the opening 21. In order to permit of manually adjusting the closure 21 so that it can be partially held in open position or open to its full extent and held in this position, I pro- 50 vide an operating member or bar 35 mounted to swing loosely on the upper extremity of the exterior end of the arm 29, the inner end of the operating member 35 being pro- 55 vided with a finger 36, which when the mem- ber is actuated, will engage the extension 31 and impart a swinging action to the closure 22 to move the same from its normal closed position into an open position. The 60 degree of opening of the closure is regu- lated by having a spring engaged catch 37 mounted to swing on the operating member 35 with a depending end 38 of the catch adapted to be received in any one of a plu- 65 rality of depressions or openings 39 in a segmental plate 40 secured to the top of the

box. This construction is provided so that the operator can secure the red glass closure in a partially or entirely open position for particular purposes, it being understood that ordinarily the closure by reason of the 70 provision of the spring rod 33 and its connections, the closure is normally retained in a closed position as to the opening 21.

Secured to the top of the box 10 is an upright 41 on which is mounted to swing an 75 operating lever 42 carrying a swingingly mounted actuating plate or finger 43, which when the lever is depressed into the position shown in Figs. 1 and 2, moves the extremity of the plate 43 against the roller 32 causing 80 the closure 22 to be swung in the manner described heretofore, from a closed to an open position. In order to normally retain the operating lever 42 in its raised or inoperative position as shown in Fig. 4, there is se- 85 cured to the top of the box adjacent the up- right 41 a curved spring-like retaining mem- ber 44 having an off-set or depressed por- 90 tion 45 with an extension 46 secured to the operating lever 42 and adapted to have its 95 extremity received in the off-set or de- pressed portion 45 of the retaining member 44 when the lever is in its vertical position so that the spring-like nature of the mate- 100 rial from which the retaining member is 95 made, will cause sufficient pressure to be ex- 105 ereted upon the extension to retain the lever in its upright position, the slight forward pressure on the upper end of the lever how- ever, being sufficient to move the extension 100 out of engagement with the retaining mem- 110 ber so that the lever will gravitate or can be swung into operating position. The seg- 115 mental plate 40 has the main portion 47 thereof provided with a plurality of up- standing ears 48 and a presser member 49, preferably consisting of two relatively 120 hinged pieces 50 carrying arms 51 which are hinged and supported to swing upon the ears 48, a chain or cable 52 having connec- 125 tion with one of the pieces of the presser member and in turn connected to the oper- 130 ating lever 42 near its free end. Adjacent this point of connection of the chain with the operating lever there is secured to the latter 115 a spring plate 53, which when the lever is de- 120 pressed as shown in Figs. 1 and 2, will bear against the upper face of one of the pieces 50 tending to press the presser mem- 125 ber tightly against the printing paper and upon depression of the operating lever to 130 have the presser member secure the printing paper against accidental displacement, a spring finger catch 54, mounted on the oper- ating lever will engage with a projection 55 on the front of the box to lock the oper- ating lever in its depressed position, thus also locking the presser member in its active po- 125 sition. By reference to Figs. 1 and 4, it will be clear that when the catch 54 is disen-

gaged from the projection 55, the operating lever can be swung upwardly into inactive position and will of course carry the presser member with it so that the printing paper and film or plate can be subsequently removed.

Formed with the main portion 47 of the plate 40 is a strip 56 having a series of upstanding pins 57 with which a mask 58 can be suitably engaged as shown in Fig. 6 and mounted to swing upon the ears 48 is a holding strip 59 having cut out portions 60 for the pins 57, the said holding strip having a rearward extension 61 engaged by a curved spring 62 to normally hold the holding strip in lowered or raised position as the case may be, it being apparent that the depression of the holding strip after the mat or other article has been arranged in position, will secure the latter against accidental displacement.

Now referring to the views it will be seen that regardless of whether the operator desires to print from a film or plate, the disposal of one of these members in position over the opening 25 and the subsequent disposal of a sheet of printing paper upon a film or plate can be readily accomplished and as mentioned heretofore the character of the film or plate can be readily determined when it is being placed in position by reason of the weak red light which permeates the front compartment 15 through the red glass of the closure separating the rear or light compartment from the front compartment. Now when the operating lever 42 is swung downwardly into locked position by reason of the provision of the finger catch 54, the presser member will also be swung forwardly and downwardly to bear against the printing paper and flatten it out and secure it against the face of the film or plate and at the moment that the operating lever is so actuated it will be apparent that the actuating plate 43 will be brought to exert a pressure against the roller 32 thus through the medium of the swiveled arm and link connection described heretofore, operating the closure 22 to swing the same into open position so that the full force of the rays of light from the lamp will be received upon the underside of the film through the medium of the interposed mirror 13 and thereby bring about the printing operation. When the printing paper has been sufficiently exposed to complete the printing operation the operating lever 42 is unlocked and swung upwardly thus carrying with it the presser member 49, thereby uncovering the printing paper so that it can be removed to be automatically treated in the usual manner. At the moment that the operating lever is swung upward the actuating plate 43 will be swung away from the roller 32, removing the pressure thereon, so

that the closure 22 will be freed and by the action of the spring rod 33 and its connection with the closure, will be swung back into normal or closed position as to the opening 21.

From the foregoing description it will be seen that the printing machine described provides not only for a mechanism whereby the red glass closure is opened to connect the light compartment with the film compartment when the machine is actuated to secure the film and printing paper in printing position, but the said closure can be independently or manually actuated to be at all times secured in a half way or full way position, depending upon the amount of light that the operator desires to have ejected or projected into the film compartment from the rear or lamp compartment and it will be further apparent that with a machine of the character described, the operation of printing from negatives, can be readily and expeditiously accomplished, the machine not only providing for accurate and efficient work, but bringing about a considerable saving of time in the carrying out of the printing of pictures or photographic productions upon printing paper, from negatives, whether they be films or plates.

Having described my invention, I claim—

1. A photographic printing machine comprising a box, an apertured partition in said box and providing a plurality of compartments therein, a lamp in one of said compartments, a negative receiving holder in the other compartment, an operating lever mounted to swing on the box, a presser member mounted to swing on the box and suspended from the operating lever to be operated therewith, a translucent closure normally closing the aperture in the said partition and a means between said lever and said closure for operating the latter to uncover the aperture upon swinging said lever to move said presser member into active position said means including an angularly movable device, a roller thereon, and an element carried by the lever for imparting partial rotation to the roller.

2. A photographic printing machine comprising a box, an apertured partition in said box and providing a plurality of compartments therein, a lamp in one of said compartments, a negative receiving holder in the other compartment, an operating lever mounted to swing on the box, a presser member mounted to swing on the box and suspended from the operating lever to be operated therewith, a translucent closure normally closing the aperture in the said partition, a rotatable device operated by frictional contact for controlling the closure and uncovering the aperture upon swinging said lever to move said presser member into active position, and a finger catch on the lever

- for engagement with the box to secure said lever in locked relation to the box and retain said presser member in active position.
3. A photographic printing machine comprising a box, an apertured partition in the box and providing a plurality of compartments, a lamp in one of the compartments, a negative holder in the other compartment, an operating lever mounted to swing on the box, a presser member controlled by said operating lever to be moved into active position when said lever is actuated, a closure for the aperture in the partition, a connection including a rotatable element between said operating lever and said closure for actuating the closure when the lever is actuated and means for independently adjusting the position of the closure relative to the aperture of the partition, said means last named including a segmental element, a swinging arm movable with reference thereto, retaining means for the arm, and a device posi-

tioned for engagement with the rotatable element.

4. A photographic printing machine, comprising a box, an apertured partition in the box providing a plurality of compartments, a lamp in one of the compartments, a negative holder in the other compartment, an operating lever mounted on the box, a pressure member controlled by the lever and moved into axial position when the lever is actuated, a closure for the aperture in the partition, a connection including a rotatable element between the lever and closure for operating the closure when the lever is actuated, and means for independently adjusting the position of the closure relative to the aperture, said means last named including an eccentrically mounted device positioned for engagement with the rotatable element.

In testimony whereof I affix my signature.

EVERETT E. SHELDON.
